COMBINATION LOCK

Frederic K. Heyer, Stamford, Conn., assignor to
 The Yale & Towne Manufacturing Company,
 Stamford, Conn., a corporation of Connecticut

Application September 16, 1943, Serial No. 502,564

48 Claims. (Cl. 70—285)

1

This invention relates to combination locks and more particularly to a combination lock that is adapted for use on lockers.

Even more particularly, my invention relates to a combination lock of the type disclosed in the Brauning Patent 2,112,982 granted April 5, 1938, and owned by the Yale & Towne Manufacturing Company to whom this application is assigned.

The object of my invention is the reduction to practice of a combination lock having several meritorious features that have long been sought by this art, and which adapt my lock for application to many different types of constructions, and for effective operation in each of the said applications.

In the Brauning patent, which incidentally is representative of the highest state of development of the prior art, the bolt of the lock is adapted for sliding motion on the lock housing in parallel relation to the usual latch bolt of the locker. The Brauning lock is handed however, and must therefore be turned about for right-hand and left-hand installations.

A feature of my lock resides in an extremely novel form of locking bolt, and in the locking bolt and lock housing relationship whereby the bolt will operate equally well on a right-hand or left-hand door without requiring the lock housing to be turned about for either installation.

In the Brauning lock, the setting of the tumblers releases the lock bolt for operation by the latch of the locker, and the said latch is equipped with a handle whereby it may be operated when the bolt of the lock is released. In other words, the combination setting dial knob of the Brauning patent is used merely to set the combination tumblers and cannot be used to retract the latch bolt of the locker, the said latch bolt having a handle secured thereto for the particular purpose.

As a feature of my invention, upon the proper setting of the combination tumblers, the lock bolt may be moved as in the Brauning lock by operation of the latch bolt of the locker. It is also possible in the very same lock, to move the bolt, and therefore the locker latch bolt, through operation of the combination setting dial knob. It is therefore possible, if desired, to dispense with the outside operating handle of the locker latch bolt when my lock is utilized. This is an extremely important feature because it adapts my lock for utilization in many types of structures additional to structures of the type illustrated in the Brauning patent, all as will be quite apparent to those skilled in the art.

A further feature of my invention resides in an extremely novel and simple type of disperser mechanism for dispersing the combination, the disperser acting preferably as the bolt is thrown into locking position.

A further feature of my lock resides in its 60 the lock.

2

adaptability for use with the automatically dropping latch bolt now applied to most lockers. Thus, my lock makes it possible for the locker latch bolt to be held up in unlocking position, to drop automatically into locking position upon closing of the locker door, to be held locked thereafter by the bolt of my lock, and with the locking operation being accompanied by the dispersal of the previously set combination.

10 A further feature of my invention resides in the mechanism whereby the bolt may be released and retracted by key operated mechanism independently of the tumblers. While such mechanism is found in the art, the means that I have evolved are extremely simple, novel and effective.

15 A further feature of my invention resides in the novel means for changing the combination of the lock and in the means whereby the combination changing means are controlled.

20 I have thus outlined the several more important features of my invention in order that the nature of my invention and its relation to the prior art may be better appreciated. A considerable number of features that will be claimed hereinafter I have not as yet outlined because they will be better understood after a reading of the specification. Those skilled in the art will appreciate that my invention may be embodied in various mechanical structures, and that it should therefore not be limited by the particular mechanical means herein to be described.

25 For a detailed description of my invention I shall refer to the drawings wherein

Fig. 1 is a vertical view of part of a locker showing my lock applied thereto.

30 Fig. 2 is a section taken along lines 2—2 of Fig. 1.

Fig. 3 is a section taken along lines 3—3 of Fig. 1.

35 Fig. 4 is a perspective view of certain of the parts of Fig. 3.

40 Fig. 5 illustrates the cooperation of the bolt of the lock with a modified form of latch bolt in which the latch bolt is moved by the dial knob of the lock rather than by a handle fixed to the latch bolt.

45 Fig. 6 is a section similar to that of Fig. 2 but illustrating the form of invention illustrated in Fig. 5.

50 Fig. 7 is a section taken along lines 7—7 of Fig. 1.

Fig. 7a is a view of the end of the dial knob assembly.

55 Fig. 8 is a section taken along lines 8—8 of Fig. 7.

Figs. 9 and 10 are sections taken respectively along lines 9—9 and 10—10 of Fig. 7.

Fig. 11 is a view of the parts of Fig. 10 illustrating the operation of the bolt by the dial knob of

60 the lock.

Fig. 12 is a section taken along lines 12—12 of Fig. 10 illustrating the form of the disperser.

Fig. 13 is a view similar to Fig. 11 illustrating the action of the disperser.

Fig. 14 is a perspective view of the bolt of my lock showing its relation to the dog.

Fig. 15 is a sectional view of the tumbler casing illustrating the construction of certain parts of the lock.

Figs. 16 and 17 are taken along lines 16—16 of Fig. 15 and illustrate the operation of the fence relatively to the dog of the bolt.

Fig. 18 is a perspective view of the fence.

Fig. 19 is an exploded view of the tumbler casing and the tumblers.

Fig. 20 is a perspective view of the tumbler casing looking at it from the rear.

Fig. 21 is a perspective view of the entire lock assembly showing the bolt in release position.

Fig. 22 is a perspective view of the entire lock assembly examined from the side opposite that shown in Fig. 21.

Fig. 23 is a section taken along lines 23—23 of Fig. 21.

Figs. 24 and 25 are views taken along lines 25—25 of Fig. 23 illustrating the action of the combination changing mechanism.

Referring now more particularly to the drawings, and especially Figs. 1 to 5 inclusive and Figs. 21 and 22, I illustrate a standard form of locker designated by reference numeral 10 and having a usual latch bolt 11 equipped with a handle 12 and locking lugs 13. As best shown in Figs. 3 and 4, the locking lugs 13 are adapted to slide behind ears 14 of a pair of strikes 15 on the main frame of the locker, it being understood that the latch bolt 11 is mounted for sliding motion on the door 16 of the locker, and locks the said door to the main frame through the intermediary of the said lugs 13 and strike ears 14.

When the locker latch bolt 11 is moved into its upper position, as allowed by its slots 17 co-operating with guide pins 18, the door 16 may be moved into open position. As the door is opened with the latch bolt 11 in its said upper position, a surface 19a of a spring detent 19 will spring into a notch 20 of the latch bolt 11 and hold that latch bolt in said upper release position. When the door is again moved to closing position, the surface 19b of the spring detent 19 will contact the edge of the lower strike 15 so as to be forced out of the notch 20 of the locker latch bolt 11. The locker latch bolt may then drop into its locking position with its locking lugs 13 behind the ears 14 of the strikes 15.

The mechanism just described is old and well known in the art, and reference is merely made thereto in order that my contribution to the art may be better understood.

Movement of the locker latch bolt 11 upwardly to its release position is prevented by the bolt 22 of my lock, best illustrated in Figs. 1, 14, 21 and 22. This bolt 22 has a pair of opposed locking lugs 23, one on each side of the lock housing so that if the lock is secured to a right-hand door, one of the lugs 23 will cooperate with an extending arm 24 of the locker latch bolt 11 as illustrated in Fig. 1. If the lock is applied to a door opening oppositely from that illustrated in Fig. 1, it is obvious that the other locking lug 23 will cooperate with the arm 24 of the locker latch bolt 11.

In the installation illustrated in Fig. 1, upon setting of the combination tumblers of the lock by the dial knob 25, the bolt 22 is released for sliding motion in an upward direction. The han-

dle 12, fixed to the locker latch bolt 11, may then move the latch bolt vertically from the position of Fig. 3 to release the door 16 for opening. The latch bolt 11 through its arm 24 and the lugs 23 of the lock bolt 22, when moved to release the door for opening, moves the bolt 22 vertically from its position of Fig. 1 to its position of Figs. 21 and 22. The bolt 22 and the locker latch bolt are then retained in their upper release position by the spring detent 19 until the door is closed. When the door is closed and detent 19 is moved, the latch bolt 11 will drop vertically into locking position and will be accompanied by the bolt 22. Thereafter the bolt 22 will be locked and will hold the latch bolt 11 locked, all as will hereinafter be set forth.

In the installation of my lock illustrated in Figs. 5 and 6, the arm 24 of the locker latch bolt is modified to take the form indicated by reference numeral 24a in Fig. 5. There the arm 24a is illustrated as having a pair of arms 24b projecting over and under the bolt lug 23 so that movement of the bolt 22 upwardly or downwardly will effect a similar movement of the latch bolt 11. The locker latch bolt 11, in the modification of Figs. 5 and 6, does not have a handle such as the handle 12 in the modification of Figs. 1 and 2. The latch bolt 11 is therefore movable only through the dial knob 25 after the setting of the combination tumblers, all as will hereinafter be set forth in detail. It is thus seen that in the modification of Figs. 1 and 2 the locker latch bolt 11 is adapted to operate the bolt 22 as said latch bolt is moved by its handle 12, whereas in the modification of Figs. 5 and 6 the bolt 22 operates the locker latch bolt as the bolt is moved by the dial knob 25. An important feature of my invention is its adaptability for use in each assembly without any adjustment or change of the parts thereof.

Referring now to Figs. 7, 9, 14, 21 and 22 it will be noted that the housing of my lock is designated by reference numeral 26, and is equipped with track ways 27 at each side thereof for the accommodation of vertical guides 28 formed as a part of the bolt 22. In other words, through the construction shown, the bolt 22 is adapted for vertical sliding motion relatively to the lock housing 26 and with its locking lugs 23 at each side of the housing all for the purposes already set forth and hereinafter to be detailed.

In Fig. 9 it will be noted that a pair of opposed springs 29 bear at their lower ends against shoulders 30 of the bolt 22 and at their upper ends against heads 31 of guide pins 32. The guide pins 32 bear partially against shoulders 33 of the bolt 22 and partially against shoulders 34 of the housing 26. As is quite apparent, the particular structure will tend to center the bolt 22 relatively to the housing 26 and yieldingly to oppose sliding motion of the bolt relatively to the housing.

The lock housing 26 is formed with a circular opening 35, as best illustrated in Figs. 9 and 21, and rotatable within this opening is what I term a tumbler casing 36, best illustrated in Figs. 19 and 20. While I prefer to use a casing to hold the tumblers in position, any holder will operate satisfactorily, and the term casing as herein used is intended to define merely a tumbler holder or tumbler mounting device. On the rear end of the tumbler casing 36 there are formed a pair of pins 37 and 38 with the pin 38 being somewhat longer than the pin 37 for reasons that

are hereinafter set forth. As shown in Fig. 19, a post 39 extends centrally from the tumbler casing 36 and is formed as an integral part of the said casing.

A series of tumblers 40 are mounted within the tumbler casing 36 and are adapted for rotation about the axis of the post 39. The tumblers 40 are assembled within the casing in any usual manner known in the art and are actuated one by the other through fingers 41 of a series of operating discs 42 assembled relatively to any one of a series of holes 43 in the tumblers, all as may be determined by the particular combination of the lock. The outermost tumbler is designated by reference numeral 44 and has formed integrally therewith a clutch disc 45 that is ratcheted at 46 for a purpose to be hereinafter set forth. An assembly washer 47 is illustrated also in Fig. 19 and its coaction with the tumbler casing 36 for holding the parts assembled within the casing is quite apparent.

The fence of my lock is of very unusual design and is designated in Fig. 18 by reference numeral 48. That part of the fence that actually enters the gatings of the tumblers is designated by reference numeral 49 and is grooved as at 50 for a spring 51 secured to the tumbler casing 36. It is the function of the spring 51, as best seen in Fig. 15, to press the fence part 49 yieldingly against the periphery of the several tumblers 40 and the outside tumbler 44, for entry into the gatings 52 of the said tumblers when those gatings are properly aligned. In Figs. 15 and 16 the fence 48 is shown out of the tumbler gatings, while in Fig. 17 the fence is shown within the tumbler gatings.

It will of course be noted that the fence 48 is slidable relatively to the tumbler casing 36 but is rotatable integrally therewith. It will therefore be appreciated that when the fence is outside the tumbler gatings, tumbler casing 36 and the fence 48 may rotate freely relatively to the tumblers, and vice versa, and that when the fence is within the gatings of the tumblers, then the tumblers and the tumbler casing are interlocked for rotation as a unit. Such rotation may then be imparted by dial knob 25 as will later be indicated.

The fence 48 is equipped with a pin 53 having a necked portion 53a that rides within a slot 54 of a dog 55. This dog is best illustrated in Figs. 7, 14, 16 and 17, as well as in other figures of the drawings. In Figs. 7, 16 and 17 it will be noted that the dog 55 is formed with a rounded head 56 resting against the inner surface 22a of the bolt 22, and is through this rounded head adapted for easy pivotal motion as well as sliding motion relatively to the said surface 22a. The rounded head 56 is bored as at 57 for mounting on a peculiarly shaped bearing pin 58 extending from a stud 59 fixed in the housing 26 of the lock as best illustrated in Fig. 7. Because of the shape of the pin 58, the dog 55 may readily pivot from the right to the left in Figs. 7, 16 and 17 with the surface of its rounded head moving relatively to the surface 22a of the bolt 22. This motion is contributed to the dog by the disc 60 secured at the end of necked portion 53a of the pin 53 of the fence 48. As the fence moves from the position of Figs. 7 and 16 to the position of Fig. 17, the disc 60 will coact with the curved surface 61 of the dog 55 to move the dog as fully illustrated in Fig. 17. This movement of the dog will of course bring its lower end away from dogging relation to a detent lug 62 extending

outwardly from the surface 22a of the bolt 22 and formed as an integral part of the bolt 22.

Ordinarily, the dog 55 will lie against a shelf 63 extending from surface 22a and in dogging relation to the detent 62, thereby preventing movement of the bolt upwardly relatively to the housing 26 from the position of Figs. 1 and 7 to the position of Figs. 21 and 22. When the tumblers are set, and the fence 48 is in the position of Fig. 17, the bolt may of course be moved to the release position of Figs. 21 and 22 as is quite apparent, since the dog 55 no longer opposes the movement of the bolt.

At this point it will be well to emphasize that the pins 37 and 38 of the tumbler casing 36 are adapted to cooperate with the under surfaces 64 of the shelf 63 for moving the bolt 22 to its position of Figs. 21 and 22 when the tumbler casing 36 is revolved in either a clockwise or a counterclockwise direction, as will hereinafter be further emphasized.

It will be well also to indicate that the cam plate 65 formed as a part of surface 22a of the bolt 22 is adapted for cooperation with the longer pin 38 of the two pins 37, 38 extending from the tumbler casing 36, for rotating the tumbler casing 36 when the bolt 22 is moved upwardly to the position of Figs. 21 and 22 by the locker latch bolt 11 as that locker latch bolt is operated by the handle 12. In other words, when the bolt 22 is actuated by the locker latch bolt 11 through the handle 12, the cam surface 65 rotates the tumbler casing 36 through the long pin 38 and with the short pin 37 by-passing the plate 65 by riding over the said plate. On the other hand, when the dial knob 25 is to be relied upon to move the latch bolt 11 with the bolt 22, it is one or the other of the pins 37 and 38 cooperating with the surface 64 of the bolt 22 that moves the said bolt. If the long pin 38 moves the bolt the short pin rides over the surface of cam 65. If the short pin 37 is used to retract the bolt through surface 64, then the long pin moves free of cam 65 because of the cut-away corner 65a of said cam.

I shall now describe in more detail the operation of the mechanism referred to. The construction of the dial knob 25 and the mechanism therein contained is not my invention, being fully illustrated in the Brauning patent referred to. It is merely necessary for the purpose of the present application to consider that the dial knob 25 is adapted to rotate the opposed driving lugs 70 best illustrated in Figs. 7 and 7a. These lugs in turn are adapted to enter slots 71 in the driving clutch member 72. This driving clutch member 72 is formed integrally with a sleeve 73 having a ratcheted flange 74 that normally is in engagement with the ratcheted surface 46 of the disc 45 secured to the tumbler 44 best illustrated in Fig. 19. In view of this relationship of the parts, rotation of the dial knob 25 will effect rotation of the tumblers 40, 44 to align the gatings 52. Once the gatings 52 are aligned as in Fig. 17, the part 49 of the fence 48 will enter those gatings. As it enters the gatings, the disc 60 secured to fence 48 through the pin 53 and the necked portion 53a will move the dog 55 out of the plane of the detent 62 of the bolt 22. The bolt will now be released for movement.

As was earlier set forth, once the fence 48 enters the several gatings 52 of the tumblers, the tumblers and the tumbler casing 36 become interlocked for movement as a unit. Therefore, with the parts in the condition set forth, the dial knob 25 may rotate the tumblers and the tumbler

casing 36. This rotation of the tumbler casing 36 is well illustrated in Fig. 11 wherein the pin 38 is shown against the under surface 64 of shelf 63 extending from the bolt 22, and cooperating with the said surface 64 to lift and hold the bolt in its release position of Figs. 21 and 22. During this movement of the parts, the dog 55 has been moved by the necked portion 53 over into the position illustrated in Fig. 11. When the parts return to their initial position upon lowering of bolt 22, the dog 55 will of course assume its normal position of Figs. 14 and 16. The operation just described is the operation that takes place when the modification of Figs. 5 and 6 is utilized; that is, when the dial knob 25 retracts bolt 22 and locker latch bolt 11.

If, with the dog 55 out of the plane of the detent lug 62 as in Fig. 17 because of the setting of the tumblers by dial knob 25, it is desired to release the latch bolt 11 through the handle 12 in the modification of Figs. 1 and 2, then the bolt 22 may be moved upwardly through latch 11 toward the position of Figs. 21 and 22. During this movement the cam plate 65 will contact the longer pin 38 of the tumbler casing 36, and will rotate that tumbler casing to the position illustrated in Fig. 13. The short pin 37 will merely glide over the cam plate 65 so as not to interfere with the action of the said cam plate. The tumbler casing 36 will rotate approximately in the same manner as in Fig. 11 carrying the dog 55 with it as illustrated in that figure.

It is highly desirable that regardless of whether the tumbler casing 36 rotates to retract the bolt 22, or is rotated by the bolt 22, the tumbler combination be dispersed. For the particular purpose a spring plate disperser 75 is utilized, being well illustrated in Figs. 10, 11, 12, 13 and 15. In Fig. 12 the fence 48 is shown as overlying the central portion 75a of the disperser 75 when the tumbler casing is in the normal locked position shown in full lines in Fig. 10. This same relation of the parts is illustrated in the side view of Fig. 16. When the fence enters the gatings of the several tumblers, it moves downwardly into the position of Fig. 17 relatively to the disperser surface 75a, and as illustrated in dotted lines in Fig. 10. It will be noted that the spring wings 76 of the disperser extend into the plane of the fence in Fig. 16, and that as the fence rotates with tumbler casing 36 to the position of Figs. 11 and 13 from the dotted line position of Fig. 10, the fence depresses one spring wing 76 of the disperser 75 and then releases that wing as it moves beyond it.

In Figs. 11 and 13 the fence 48 is shown beyond one of the wings 76 of the disperser. If now the tumbler casing is rotated in a reverse direction incidental to the dropping of the bolt 22 from its position of Figs. 21 and 22 to its position of Fig. 7, the fence 48 will of course rotate with the tumbler casing 36. Its end surface will abut the wing 76 of the disperser and will be moved by that wing out of the tumbler gatings to the position of Fig. 15. This motion takes place during the first part of the movement of the tumbler casing from the position of Figs. 11 and 13 to the position of Fig. 15. Once the fence is outside the tumbler gatings, it is moved with the tumbler casing 36 relatively to the tumblers, so as to disperse the combination. When the parts return to their position of Fig. 15 the fence is of course outside of the gatings and the mechanism is once again locked.

As already set forth, it is necessary to operate the dial knob 25 and the parts rotatable therewith in order to set the tumblers with their gatings in alignment, and thus release the bolt 22 for 5 sliding movement by the tumbler casing 36 or by movement of the latch bolt 11. In other words, the dog 55 must be moved out of the plane of the lug 62 to the position of Fig. 17 through the setting of the tumblers, if the bolt 22 is to be 10 retracted either through the tumbler casing 36 by pins 37 and 38, or by the locker latch bolt 11. It is also to be noted that regardless of whether the bolt is moved by the locker latch bolt 11 or by the tumbler casing 36 directly, the combination 15 is dispersed when the bolt 22 is moved back to locking position.

Within the dial knob 25 there is mounted a key plug 80 and this key plug controls the rotation of a sleeve 81 as fully set forth in the Brauning patent. If it is desired to retract the bolt 20 without setting up the combination tumblers, it is possible to do this by the operation of the key plug 80 and sleeve 81, utilizing the key 82. As best illustrated in Figs. 7 and 7a, the lug 63 of the 25 sleeve 81 is adapted to enter the arcuate slot 84 of post 39 as the sleeve 81 is inserted over the central post 39 of the tumbler casing. Thereafter, the central post 39 may be rotated by the key plug through sleeve 81 to effect rotation of the 30 tumbler casing 36, all without the intermediary of the fence 48 and the initial movement of dog 55.

Rotation of the tumbler casing 36 by the operation of key plug 80 first acts to rotate the dog 55 35 through the necked portion 53a of pin 53 of the fence 48. This rotation will move the dog 55 away from the detent lug 62 of the bolt 22. Continued rotation of tumbler casing 36 of course acts to move the bolt 22 to its release position just as 40 in the case where the tumbler casing 36 is rotated through the intermediary of the tumblers with the dial knob 25. It is thus seen that I have devised an extremely simple structure for the 45 operation of the mechanism by a key, where such operation is desirable.

It is many times required to reset the combination of the lock. In my structure this may be done by first separating the ratcheted flange 14 50 of sleeve 73 on driving clutch member 72, from the teeth 46 of the disc 45 shown in Fig. 19. For this purpose there is utilized a control slide 85 best illustrated in Fig. 21 and shown in operation in Figs. 7, 23, 24 and 25. In the position of the parts in Figs. 7 and 24, the cam surface 86 of 55 the slide 85 is maintained against the ratcheted flange 14, holding the driving clutch member 72 in position with the teeth of the flange 14 in engagement with the teeth 46. The enlarged opening 87 of slide 85 is opposite the shouldered portion 88 of the sleeve 73 of which flange 14 is an integral part. This is of course the normal relationship of the parts when the slide 85 is in the 60 position of Figs. 7, 21 and 24.

If the bolt 22 is now moved to its release position of Fig. 22, a keyway 89 is exposed and a key 65 90 may be inserted into this keyway to bring its bitted portion 91 into contact with a part of the slide 85 as is best illustrated in Figs. 21, 23 and 25. Rotation of the key 90 may now be utilized 70 to move the slide 85 on its bearings formed on the lock casing 36, from the position of Figs. 7, 21 and 24 to the position of Figs. 23 and 25. The narrow portion 92 of the opening in the slide 85 is, during this motion, adapted to coact with the 75 shouldered portion 88 of the sleeve 73 to move

the parts 72, 73, 74 to the left from the position of Fig. 7 and into the position of Fig. 23.

There is now no longer engagement of the teeth of flange 74 and the teeth 46 of the disc 45 secured to tumbler 44. The dial knob 25 may therefore now be rotated to move the said dial knob relatively to the series of tumblers so as to change the combination. Once this combination is changed, the key 90 moves the slide 85 back to its position of Figs. 7, 21 and 24 to bring the teeth of flange 74 back into engagement with the teeth 46 and resume the driving relationship between the dial knob 25 and the tumblers. The tumblers will of course now be operated in accordance with the new combination.

I believe that from the outlined description first given in the specification, the detailed description later given, and the several reviews of the mechanism presented in this specification, the operation of my invention will now be quite apparent to those skilled in the art.

I now claim:

1. In a lock of the class described, a housing having opposed parallel sides, a bolt, means on the outside faces of said opposed sides of said housing forming a bearing for said bolt, and parts of said bolt riding on each of said bearings for sliding movement relatively to said housing.

2. In a lock of the class described, a housing having opposed parallel sides, a bolt, means on the said opposed sides of said housing forming a bearing for said bolt, parts of said bolt riding on each of said bearings for sliding movement relatively to said housing, and a bolt lug extending from said bolt at each side of said housing.

3. In a lock of the class described, a housing, a bolt mounted for movement in a fixed plane relatively to said housing and having a detent portion, a dog in said housing having a part thereof lying in the plane of said detent portion to block movement of said bolt in said fixed plane, and means for moving said dog angularly to the plane of said detent and the said fixed plane whereby to bring said part out of obstructing relation to said detent.

4. In a lock of the class described, a housing, a bolt mounted for movement in a fixed plane relatively to said housing and having a detent portion, a dog pivoted in said housing and having a part thereof lying in the plane of said detent portion to block movement of said bolt, a series of combination tumblers, and means controlled by the setting of said tumblers for moving said dog angularly on its pivot, whereby to move said part of the dog angularly relatively to the plane of said detent portion and said fixed plane out of locking relation to said bolt detent.

5. In a lock of the class described, a housing, a bolt mounted for movement in a fixed plane relatively to said housing and having a detent portion, a dog, a universal pivot mounting for said dog in said housing, a part of said dog normally lying in the plane of said detent portion to block movement of said bolt, a series of combination tumblers, means controlled by the setting of said tumblers for moving said dog on its pivot and said part of the dog angularly out of the plane of said detent portion, and key operated means for moving said dog on said universal pivot to one side of said detent.

6. In a lock of the class described, a housing, a bolt movable on said housing between retracted and projected positions, a dog for dogging said bolt against movement, a tumbler casing mounted for rotation in said housing, means whereby

rotation of said casing retracts said bolt, tumblers having gatings rotatable in said tumbler casing, a fence movable to release position into said gatings when said tumblers are properly positioned with said gatings aligned, means whereby said fence when moved to release position moves said dog out of dogging relation to said bolt, and means whereby said fence when in said gatings interlocks said tumbler casing and said tumblers so that rotation of said tumblers thereafter rotates said tumbler casing to retract said bolt.

7. In a lock of the class described, a housing, a bolt movable on said housing between retracted and projected positions, a dog for dogging said bolt against movement, a tumbler casing mounted for rotation in said housing, means whereby rotation of said casing retracts said bolt, tumblers having gatings rotatable in said tumbler casing, a fence movable to release position into said gatings when said tumblers are properly positioned with said gatings aligned, means whereby said fence when moved to release position moves said dog out of dogging relation to said bolt, means whereby said fence when in said gatings interlocks said tumbler casing and said tumblers so that rotation of said tumblers thereafter rotates said tumbler casing to retract said bolt, a disperser by-passed by said fence as it rotates with said tumblers and casing to retract said bolt, said disperser moving said fence out of said tumbler gatings upon return rotation of said tumbler casing.

8. In a lock of the class described, a housing, a bolt movable on said housing between retracted and projected positions, a dog for dogging said bolt against movement, a tumbler casing mounted for movement in said housing, means whereby movement of said casing retracts said bolt, tumblers having gatings rotatable in said tumbler casing, a fence movable to release position into said gatings when said tumblers are properly positioned with said gatings aligned, means whereby said fence when moved to release position moves said dog out of dogging relation to said bolt, and means whereby said fence when in said gatings interlocks said tumbler casing and said tumblers so that movement of said tumblers thereafter moves said tumbler casing to retract said bolt.

9. In a lock of the class described, a housing, a bolt movable on said housing between retracted and projected positions, a dog for dogging said bolt against movement, a tumbler casing mounted for movement in said housing, means whereby movement of said tumbler casing retracts said bolt, or retraction of said bolt moves said tumbler casing, tumblers having gatings rotatable in said tumbler casing, a fence movable to release position into said gatings when said tumblers are properly positioned with said gatings aligned, means whereby said fence when moved to release position moves said dog out of dogging relation to said bolt, and means whereby said fence when in said gatings interlocks said tumbler casing and said tumblers so that movement of said tumblers thereafter moves said tumbler casing to retract said bolt, or retraction of said bolt moves said tumbler casing and tumblers.

10. In a lock of the class described, a housing, a bolt movable on said housing between retracted and projected positions, a dog for dogging said bolt against movement, a tumbler casing mounted for rotation in said housing, means whereby rotation of said tumbler casing retracts said bolt,

or retraction of said bolt rotates said tumbler casing, tumblers having gatings rotatable in said tumbler casing, a fence movable to release position into said gatings when said tumblers are properly positioned with said gatings aligned, means whereby said fence when moved to release position moves said dog out of dogging relation to said bolt, means whereby said fence when in said gatings interlocks said tumbler casing and said tumblers so that rotation of said tumblers thereafter rotates said tumbler casing and tumblers, a disperser by-passed by said fence as it rotates with said tumblers and tumbler casing to retract said bolt, said disperser moving said fence out of said tumbler gatings upon return rotation of said tumbler casing.

11. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence movable into gatings in said tumblers upon proper alignment of said tumblers and adapted to interlock said tumblers and tumbler casing when so moved, and means for locking said bolt against retraction controlled by said fence whereby to release said bolt for retraction when said fence enters said gatings.

12. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence movable into gatings in said tumblers upon proper alignment of said tumblers and adapted to interlock said tumblers and tumbler casing when so moved, means for locking said bolt against retraction controlled by said fence whereby to release said bolt for retraction when said fence enters said gatings, and means whereby said bolt rotates said tumbler casing when pressure is applied to said bolt to move it to its retracted position after said fence controlled locking means releases said bolt for retraction.

13. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence movable into gatings in said tumblers upon proper alignment of said tumblers and adapted to interlock said tumblers and tumbler casing when so moved, means for locking said bolt against retraction controlled by said fence whereby to release said bolt for retraction when said fence enters said gatings, and manual means for rotating said tumblers to first align the gatings thereof for entry of said fence and thereafter to rotate said tumbler casing to retract said bolt.

14. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence movable into gatings in said tumblers upon proper alignment of said tumblers and adapted to interlock said tumblers and tumbler casing when so moved, means for locking said bolt against retraction controlled by said fence whereby to release said bolt for retraction when said fence enters said gatings, a disperser by-

passed by said fence as it rotates with said tumblers and casing to retract said bolt, said disperser moving said fence out of said tumbler gatings upon return rotation of said tumbler casing.

5 15. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence movable into gatings in said tumblers upon proper alignment of said tumblers and adapted to interlock said tumblers and tumbler casing when so moved, means for locking said bolt against retraction controlled by said fence whereby to release said bolt for retraction when said fence enters said gatings, manual means for rotating said tumblers to first align the gatings thereof for entry of said fence and thereafter to rotate said tumbler casing to retract said bolt, a disperser by-passed by said fence as it rotates with said tumblers and casing to retract said bolt, said disperser moving said fence out of said tumbler gatings upon return rotation of said tumbler casing.

16. In a lock of the class described, a housing, a bolt movable on said housing between retracted and projected positions, a tumbler casing mounted for rotation in said housing, means whereby rotation of said tumbler casing moves said bolt into its retracted position, tumblers mounted for rotation in said casing, a fence movable into gatings in said tumblers upon proper alignment of said tumblers and adapted to interlock said tumblers and tumbler casing when so moved, means for locking said bolt against retraction controlled by said fence whereby to release said bolt for retraction when said fence enters said gatings, key operated means for rotating said tumbler casing independently of said tumblers, said fence moving with said tumbler casing to release said bolt from said locking means as said tumbler casing is rotated.

17. In a lock of the class described, a housing, a bolt movable on said housing between retracted and projected positions, a tumbler casing mounted for rotation in said housing, means whereby rotation of said tumbler casing moves said bolt into its retracted position, a central post extending from said tumbler casing, tumblers mounted on said post for rotation in said casing, a fence movable into gatings in said tumblers upon proper alignment of said tumblers and adapted to interlock said tumblers and tumbler casing when so moved, means for locking said bolt against retraction controlled by said fence whereby to release said bolt for retraction when said fence enters said gatings, key operated means for rotating said central post independently of said tumblers whereby to rotate said tumbler casing independently of said tumblers, said fence moving with said tumbler casing to release said bolt from said locking means as said tumbler casing is rotated.

18. In a lock of the class described, a housing, a bolt movable on said housing between retracted and projected positions, a dog for dogging said bolt against movement, a tumbler casing mounted for rotation in said housing, means whereby rotation of said casing retracts said bolt, tumblers having gatings rotatable in said tumbler casing, a fence movable to release position into said gatings when said tumblers are properly positioned with said gatings aligned, means whereby said fence when moved to release po-

sition moves said dog out of dogging relation to said bolt, means whereby said fence when in said gatings interlocks said tumbler casing and said tumblers so that rotation of said tumblers thereafter rotates said tumbler casing to retract said bolt, and key operated means for rotating said tumbler casing independently of said tumblers.

19. In a lock of the class described, a housing, a bolt movable on said housing between retracted and projected positions, a dog for dogging said bolt against movement, a tumbler casing mounted for rotation in said housing, means whereby rotation of said casing retracts said bolt, tumblers having gatings rotatable in said tumbler casing, a fence movable to release position into said gatings when said tumblers are properly positioned with said gatings aligned, means whereby said fence when moved to release position moves said dog out of dogging relation to said bolt, means whereby said fence when in said gatings interlocks said tumbler casing and said tumblers so that rotation of said tumblers thereafter rotates said tumbler casing to retract said bolt, and key operated means for rotating said tumbler casing independently of said tumblers, said rotation of said casing by said key rotating said fence and through said fence moving said dog out of dogging position.

20. In a lock of the class described, a housing, a bolt movable on said housing between retracted and projected positions, a tumbler casing mounted for rotation in said housing, means whereby rotation of said tumbler casing moves said bolt into its retracted position, a central post extending from said tumbler casing, tumblers mounted on said post for rotation in said casing, a fence movable into gatings in said tumblers upon proper alignment of said tumblers and adapted to interlock said tumblers and tumbler casing when so moved, means for locking said bolt against retraction controlled by said fence whereby to release said bolt for retraction when said fence enters said gatings, and key operated means for rotating said central post independently of said tumblers whereby to rotate said tumbler casing independently of said tumblers.

21. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence rotatable with said tumbler casing and slidably mounted thereon for movement into gatings in said tumblers upon proper alignment of said tumblers whereby to interlock said tumblers and tumbler casing when so moved, and means for locking said bolt against retraction controlled by said fence adapted to release said bolt for retraction when said fence moves into said gatings and when said fence rotates with said tumbler casing while remaining outside of said gatings.

22. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence rotatable with said tumbler casing and slidably mounted thereon for movement into gatings in said tumblers upon proper alignment of said tumblers whereby to interlock said tumblers and tumbler casing when so moved, means for locking said bolt against retraction controlled by said fence to release said bolt for

retraction when said fence moves into said gatings and when said fence rotates with said tumbler casing while remaining outside of said gatings, and manual means for rotating said tumblers to first align the gatings thereof for entry of said fence and thereafter to rotate said tumbler casing through said tumblers to retract said bolt.

23. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence rotatable with said tumbler casing and slidably mounted thereon for movement into gatings in said tumblers upon proper alignment of said tumblers whereby to interlock said tumblers and tumbler casing when so moved, means for locking said bolt against retraction controlled by said fence to release said bolt for retraction when said fence moves into said gatings and when said fence rotates with said tumbler casing while remaining outside of said gatings, manual means for rotating said tumblers to first align the gatings thereof for entry of said fence and thereafter to rotate said tumbler casing through said tumblers to retract said bolt, and key operated means for rotating said tumbler casing independently of said tumblers and fence.

30. 24. In a lock of the class described, a housing, a bolt movable on said housing between retracted and projected positions, a tumbler casing mounted for rotation in said housing, means whereby rotation of said tumbler casing moves said bolt into its retracted position, a central post extending from said tumbler casing, tumblers mounted on said post for rotation in said casing, a fence rotatable with said tumbler casing and slidably mounted thereon for movement into gatings in said tumblers upon proper alignment of said tumblers whereby to interlock said tumblers and tumbler casing when so moved, and means for locking said bolt against retraction controlled by said fence to release said bolt for retraction when said fence moves into said gatings and when said fence rotates with said tumbler casing while remaining outside of said gatings.

35. 25. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence rotatable with said tumbler casing and slidably mounted thereon for movement into gatings in said tumblers upon proper alignment of said tumblers whereby to interlock said tumblers and tumbler casing when so moved, means for locking said bolt against retraction controlled by said fence to release said bolt for retraction when said fence moves into said gatings and when said fence rotates with said tumbler casing while remaining outside of said gatings, and key operated means for rotating said tumbler casing independently of said tumblers.

40. 26. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence rotatable with said tumbler casing and slidably mounted thereon for movement into gatings in said tumblers upon proper alignment of said tumblers whereby to interlock said tum-

blers and tumbler casing when so moved, a dog pivoted on said housing and held positioned to dog retractive movement of said bolt when said fence is outside said gatings and said casing is in an initial position, and means whereby said fence moves said dog out of dogging relation to said bolt when said fence moves into said tumbler gatings and when said fence rotates with said casing while out of said tumbler gatings.

27. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence rotatable with said tumbler casing and slidably mounted thereon for movement into gatings in said tumblers upon proper alignment of said tumblers whereby to interlock said tumblers and tumbler casing when so moved, a dog pivoted on said housing and held positioned to dog retractive movement of said bolt when said fence is outside said gatings and said casing is in an initial position, means whereby said fence moves said dog out of dogging relation to said bolt when said fence moves into said tumbler gatings and when said fence rotates with said casing while out of said tumbler gatings, and key operated means for rotating said tumbler casing independently of said tumblers for moving said fence to move the dog out of dogging relation to the bolt.

28. In a lock of the class described, a housing, a bolt movable on said housing between retracted and projected positions, a tumbler casing mounted for rotation in said housing, means whereby rotation of said tumbler casing moves said bolt into its retracted position, tumblers in said tumbler casing, a fence rotatable with said tumbler casing and slidably mounted thereon for movement into gatings in said tumblers upon proper alignment of said tumblers whereby to interlock said tumblers and tumbler casing when so moved, means for locking said bolt against retraction controlled by said fence to release said bolt for retraction when said fence moves into said gatings and when said fence rotates with said tumbler casing while remaining outside of said gatings, a disperser by-passed by said fence as it rotates with said tumblers and casing to retract said bolt, said disperser moving said fence out of said tumbler gatings upon return rotation of said tumbler casing.

29. In a lock of the class described, a housing, a bolt movable on said housing between retracted and projected positions, a tumbler casing mounted for rotation in said housing, a surface on said tumbler casing adapted to contact a surface of said bolt when said tumbler casing rotates in one direction to retract said bolt, a surface on said tumbler casing adapted to contact a surface of said bolt when said casing rotates in the opposite direction to retract said bolt, tumblers in said tumbler casing, a fence controlled by said tumblers, and means whereby said fence prevents retraction of said bolt until it moves into gatings of said tumblers.

30. In a lock of the class described, a housing, a bolt movable on said housing between retracted and projected positions, a tumbler casing mounted for rotation in said housing, means whereby said tumbler casing retracts said bolt when it is rotated, tumblers in said tumbler casing having gatings, a fence controlled by said tumblers, and means whereby said fence dogs said bolt against

retraction until it moves into the gatings of said tumblers.

31. In a lock of the class described, a housing, a bolt movable on said housing between retracted and projected positions, a tumbler casing mounted for rotation in said housing, means whereby rotation of said casing retracts said bolt, tumblers having gatings rotatable in said tumbler casing, a fence movable to release position into said gatings when said tumblers are properly positioned with said gatings aligned, a dog for said bolt, means whereby said fence moves said dog out of dogging position as said fence enters said gatings, and means whereby said fence when in said gatings interlocks said tumbler casing and said tumblers so that rotation of said tumblers thereafter rotates said tumbler casing to retract said bolt.

32. In a lock of the class described, a housing, a bolt movable on said housing between retracted and projected positions, a tumbler casing mounted for rotation in said housing, means whereby rotation of said casing retracts said bolt, tumblers having gatings rotatable in said tumbler casing, a fence movable to release position into said gatings when said tumblers are properly positioned with said gatings aligned, a dog for said bolt, means whereby said fence moves said dog out of dogging position as said fence enters said gatings, means whereby said fence when in said gatings interlocks said tumbler casing and said tumblers so that rotation of said tumblers thereafter rotates said tumbler casing to retract said bolt, key operated means for rotating said tumbler casing independently of said tumblers, and said fence moving said dog out of dogging position as it rotates with said tumbler casing whereby to release said bolt.

33. In a lock of the class described, a housing, a bolt movable on said housing between retracted and projected positions, a tumbler casing mounted for rotation in said housing, means whereby rotation of said casing retracts said bolt, tumblers having gatings rotatable in said tumbler casing, a fence movable to release position into said gatings when said tumblers are properly positioned with said gatings aligned, means whereby said fence when in said gatings interlocks said tumbler casing and said tumblers so that rotation of said tumblers thereafter rotates said tumbler casing to retract said bolt, a disperser by-passed by said fence as it rotates with said tumblers and casing to retract said bolt, said disperser moving said fence out of said tumbler gatings upon return rotation of said tumbler casing.

34. In a lock of the class described, a housing, a bolt movable on said housing between retracted and projected positions, a tumbler casing mounted for rotation in said housing, means whereby said tumbler casing retracts said bolt when it is rotated, means whereby pressure against said bolt urging it toward a retracted position rotates said tumbler casing, tumblers in said tumbler casing having gatings, a fence controlled by said tumblers, and means whereby said fence prevents retraction of said bolt until it moves into the gatings of said tumblers.

35. In a lock of the class described, a housing, a bolt movable on said housing between retracted and projected positions, a tumbler casing mounted for rotation in said housing, means whereby rotation of said tumbler casing moves said bolt into its retracted position, means whereby pressure against said bolt urging it toward a re-

tracted position rotates said tumbler casing, tumblers in said tumbler casing, a fence movable into gatings in said tumblers upon proper alignment of said tumblers and adapted to interlock said tumblers and tumbler casing when so moved, and means for locking said bolt against retraction controlled by said fence whereby to release said bolt for retraction when said fence enters said gatings.

36. In a lock of the class described, a housing, a bolt movable on said housing between retracted and projected positions, a tumbler casing mounted for rotation in said housing, means whereby rotation of said tumbler casing moves said bolt into its retracted position, means whereby pressure against said bolt urging it toward a retracted position rotates said tumbler casing, tumblers in said tumbler casing, a fence movable into gatings in said tumblers upon proper alignment of said tumblers and adapted to interlock said tumblers and tumbler casing when so moved, means for locking said bolt against retraction released by said fence when said fence enters said gatings, a disperser by-passed by said fence as it rotates with said tumblers and casing to retract said bolt, said disperser moving said fence out of said tumbler gatings upon return rotation of said tumbler casing.

37. In a lock of the class described, a housing, a bolt movable on said housing between retracted and projected positions, a tumbler casing mounted for rotation in said housing, a surface on said tumbler casing adapted to contact a surface of said bolt when said casing rotates in one direction to retract said bolt, a surface on said bolt adapted to rotate the tumbler casing upon application of pressure against said bolt urging it toward its retracted position, tumblers in said tumbler casing having gatings, a fence controlled by said tumblers, and means whereby said fence prevents retraction of said bolt until it moves into the gatings of said tumblers.

38. In a lock of the class described, a housing, a bolt movable on said housing between retracted and projected positions, a tumbler casing mounted for rotation in said housing, a pin on said tumbler casing adapted to impinge against a surface on said bolt when said tumbler casing is rotated in one direction whereby to move the bolt to its retracted position, a second pin on said tumbler casing adapted to impinge against a surface on said bolt when said tumbler casing is rotated in a reverse direction whereby to move the bolt to its retracted position, a surface on said bolt adapted to impinge against one of said pins to rotate said casing when pressure is applied to said bolt urging it toward its retracted position, tumblers in said tumbler casing, a fence movable into gatings in said tumblers upon proper alignment of said tumblers and adapted to interlock said tumblers and tumbler casing when so moved, and means for locking said bolt against retraction controlled by said fence adapted to release said bolt for retraction when said fence enters said gatings.

39. In a lock of the class described, a housing, a bolt movable on said housing between retracted and projected positions, a tumbler casing mounted for rotation in said housing, a pin on said tumbler casing adapted to impinge against a surface on said bolt when said tumbler casing is rotated whereby to move the bolt to its retracted position, a surface on said bolt adapted to impinge against said pin to rotate said casing when pressure is applied to said bolt urging it toward

its retracted position, tumblers in said tumbler casing, a fence movable into gatings in said tumblers upon proper alignment of said tumblers and adapted to interlock said tumblers and tumbler casing when so moved, means for locking said bolt against retraction controlled by said fence adapted to release said bolt for retraction when said fence enters said tumbler gatings, a disperser by-passed by said fence as it moves with said tumbler casing incidental to the movement of said bolt to its retracted position, said disperser moving said fence out of said gatings when said fence and tumbler casing move as said bolt is projected, whereby said fence is thereafter moved with said tumbler casing relatively to said tumbler gatings.

40. In a lock of the class described, a housing, a bolt movable on said housing between retracted and projected positions, a tumbler casing mounted for rotation in said housing, a pin on said tumbler casing adapted to impinge against a surface on said bolt when said tumbler casing is rotated in one direction whereby to move the bolt to its retracted position, a surface on said bolt adapted to impinge against said pin to rotate said casing when pressure is applied to said bolt urging it toward its retracted position, tumblers in said tumbler casing, a fence movable into gatings in said tumblers upon proper alignment of said tumblers and adapted to interlock said tumblers and tumbler casing when so moved, and means for locking said bolt against retraction controlled by said fence whereby to release said bolt for retraction when said fence enters said gatings, a spring plate depressed by a surface of said fence as it moves with said tumbler casing incidental to the movement of said bolt to its retracted position, said spring plate springing into contact with a second surface of said fence for moving said fence out of said gatings when said fence and tumbler casing move with said bolt as said bolt is projected whereby said fence is thereafter moved with said tumbler casing relatively to said tumbler gatings.

41. In a lock of the class described, a tumbler casing, a series of tumblers rotatably mounted in said casing, a fence mounted on bearing surfaces of said tumbler casing for sliding movement relatively to said casing and for rotation therewith, a spring bearing between said casing and said fence for urging said fence toward gatings in said tumblers and for entry into said gatings when said gatings are aligned, a dog pivotally mounted in said lock, and means whereby sliding movement of said fence moves said dog on its pivot.

42. In a lock of the class described, a tumbler casing, a series of tumblers rotatably mounted in said casing, a fence mounted on bearing surfaces of said tumbler casing for sliding movement relatively to said casing and for rotation therewith, said fence being movable into gatings of said tumblers for interlocking said tumblers and tumbler casing for rotation as a unit, a dog movably mounted in said lock, and means of connection between said fence and dog whereby movement of said fence into said gatings pivots said dog in one direction, and rotation of said fence with said casing when said fence is out of said gatings, pivots said dog in another direction.

43. In a lock of the class described, a tumbler casing having a central post integral therewith, a series of tumblers rotatably mounted on said central post, a fence mounted on bearing surfaces of said tumbler casing for sliding movement

relatively to said casing and for rotation therewith, said fence being movable into gatings of said tumblers for interlocking said tumblers and tumbler casing for rotation as a unit, and means engaging said central post for rotating said tumbler casing independently of said tumblers when said fence is out of said tumbler gatings.

44. In a lock of the class described, a series of combination tumblers having gatings, a fence adapted to enter said gatings when said tumblers are properly aligned, means for rotating said tumblers and fence toward a release position once said fence is in said gatings, a disperser in the path of said fence and displaced by a surface of said fence as said fence rotates with said tumblers toward said release position, and said disperser cooperating with another surface of said fence as said fence rotates in a reverse direction from said release position for moving said fence out of said gatings.

45. In a lock of the class described, a series of combination tumblers having gatings, a fence adapted to enter said gatings when said tumblers are properly aligned, means for rotating said tumblers and fence toward a release position once said fence is in said gatings, a disperser yieldingly held in the path of said fence and displaced by a surface of said fence as said fence rotates with said tumblers toward said release position, and said disperser being non-yielding relatively to said fence as said fence rotates in a reverse direction from said release position for moving said fence out of said gatings.

46. In a lock of the class described, a series of combination tumblers having gatings, a fence adapted to enter said gatings when said tumblers are properly aligned, means for rotating said tumblers and fence toward a release position once said fence is in said gatings, a spring plate in the path of said fence and underlying said fence so as to be cammed by the said fence out of obstructing relation thereto without exerting a force urging said fence out of the tumbler gatings, said fence passing beyond the end of the plate as the fence moves to said release

position whereby to allow the spring plate to move into obstructing relation to a surface of the fence as said fence rotates in a reverse direction from said release position for moving said fence out of said gatings.

47. In a lock of the class described, a housing, a bolt movable in said housing between projected and retracted positions, a dog pivotally mounted in said housing for rotary movement about the axis of its pivotal mounting, a detent lug on said bolt adapted to abut said dog upon attempted movement of said bolt prior to rotary movement of said dog on its pivotal mounting to one side of said detent lug, and said pivotal mounting allowing pivotal motion of said dog at substantially right angles to its said rotary movement to carry said dog out of the plane of said detent lug.

48. In a lock of the class described, a housing, a bolt movable on said housing between projected and retracted positions, a dog substantially universally mounted in said housing, a detent lug on said bolt adapted to abut said dog to block retraction of said bolt, a tumbler casing rotatable on said housing, a fence slideable on said casing and rotatable therewith, a pin extending from said fence and into a slot in said dog for rotating said dog out of dogging relation to said bolt detent when said tumbler casing is rotated, and cam means whereby the pin of said fence moves said dog on its mounting means out of the plane of said bolt detent when said fence slides relatively to said tumbler casing and bolt.

FREDERIC K. HEYER.
